CLAIM

I claim the ornamental design for a lighting fixture, as shown and described.

DESCRIPTION

FIG. 1 is a front perspective view of the lighting fixture showing a first embodiment of the new design. Excluding the surface ornamentation, this fixture has mirror image symmetry about a vertical imaginary plane. The shade has a circular horizontal cross-section;

FIG. 2 is a left side elevation view of the lighting fixture of FIG. 1;

FIG. 3 is a top plan view of the lighting fixture of FIG. 1; FIG. 4 is a front perspective view of the lighting fixture showing a second embodiment of the new design. Excluding the surface ornamentation, this fixture has mirror image symmetry about a vertical imaginary plane. The shades each have a circular horizontal cross-section;

FIG. 5 is a left side elevation view of the lighting fixture of FIG. 4;

FIG. 6 is a top plan view of the lighting fixture of FIG. 4; FIG. 7 is a front perspective view of the lighting fixture showing a third embodiment of the new design. Excluding the surface ornamentation, the fixture has mirror image symmetry about a vertical imaginary plane. The shades each have a circular horizontal cross-section;

FIG. 8 is a left side elevation view of the lighting fixture of FIG. 7; and,

FIG. 9 is a top plan view of the lighting fixture of FIG. 7. The broken lines shown in the drawings depict portions of the lighting fixture that form no part of the claimed design.
